UNITED STATES PATENT OFFICE.

ROBERT GRUNDY BROOKE, OF MACCLESFIELD, ENGLAND.

INJECTOR.

SPECIFICATION forming part of Letters Patent No. 580,762, dated April 13, 1897.

Application filed July 15, 1896. Serial No. 599,273. (Model.)

To all whom it may concern:

Be it known that I, ROBERT GRUNDY BROOKE, a subject of the Queen of Great Britain and Ireland, residing at Macclesfield, 5 in the county of Chester, England, have invented Improvements in Injectors, of which the following is a specification.

This invention has reference to improvements in exhaust-steam injectors, and has for its object to increase the efficiency of such injectors, as I shall now proceed to describe with reference to the accompanying drawings, in which—

Figure 1 is a vertical section, and Fig. 2 a horizontal section on the line xx of Fig. 1, showing one construction of exhaust-steam injector according to this invention. Figs. 3, 4, and 5 are part vertical sections showing modified constructions of such injectors.

In an exhaust-steam injector according to this invention the exhaust-steam nozzle 1 is moved endwise for the purpose of regulating the cross-sectional area for water between its inner end 1^a and the interior of a fixed combining-nozzle 2 by being screwed into the injector-casing 3, as at 3^a, and being turned in one direction or the other by means either of a worm 4, that gears with a worm-wheel 5, fast on the exterior of the nozzle 1, as shown in Figs. 1 and 2, or by means of a pinion 4^a, that gears with a spur-wheel 5^a, fast on the said nozzle, as shown in Fig. 3, the worm or pinion being fixed upon a regulating-spindle 6, extending to the exterior of the casing 3 through a stuffing-box or tubular guide 7, fixed either in the side, Figs. 1 and 2, or end, Fig. 3, of the casing, according as a worm or pinion is used, the arrangement being such that by rotating the worm or pinion the steam-nozzle 1 will be moved endwise in one direction or the other, according to the direction of rotation. The worm or pinion is formed with a conical portion or valve 4^b, which by being pressed against the coned inner end of the guide 7 prevents escape of steam at this point.

6^b is a hand regulating-wheel fixed on the spindle.

The injector may be so constructed that when provided with a central solid spindle 8, Figs. 1 and 2, or hollow steam-spindle 9, Fig.

3, or spindles 9^a, Fig. 4, passing through the exhaust-steam nozzle 1, the latter and also the exhaust-steam-supply chamber 10 will have a clear way therethrough unobstructed 55 by cross-bars or other means of attachment for the spindle or spindles, thereby enabling the steam to act more efficiently than in exhaust-steam injectors as heretofore usually constructed. For this purpose the movable 60 exhaust-steam nozzle 1 may, as shown in Fig. 3, be made with an open end 1^b, that is, without the usual cross-bars, perforated walls, or other obstructions, and is in free communication with the exhaust-steam-supply chamber 65 10, which is in communication with a lateral exhaust-steam-supply passage 10^a. The nozzle 1 is inserted through a hole that is formed in the end of the injector-casing 3 at 11 and is normally closed by an end cap or cover 12, 70 to which the centrally-arranged spindle or spindles is or are fixed. In some cases, however, it is found desirable to continue the steam-nozzle 1 through the steam-space 10, as shown in Fig. 1, so as to obtain a guide or 75 bearing in the cap 12 for the upper end of the nozzle in addition to the lower bearing 3, so that any tendency of the nozzle to cant and seize, by reason of the action of the worm 4 on the worm-wheel 8, when the direction of 80 rotation is reversed will be obviated. In this arrangement the nozzle 1 may be screwed into its lower bearing 3, as shown at 3^a, or in its upper bearing, and the nozzle is formed with lateral inlet-openings 1^c for passage of 85 steam to its interior from the steam-chamber 10. Any possible canting or seizing action of the nozzle 1 can also be obviated by suitably lengthening the lower bearing 3.

When a live-steam jet is to be employed, 90 as would be the case when the injector is required to work against a higher pressure than it would with exhaust-steam alone, the spindle is made hollow, as shown at 9 in Fig. 3, and live steam is supplied to it by a pipe 13, 95 connected by a union 13^a with the central projecting portion 12^a of the end cap or cover, which has a hole 12^b through its center in connection with the hollow spindle.

In the modified construction shown in Fig. 100 4 the live-steam spindle carried by the perforated cap or cover 12 instead of being single,

as in Fig. 3, is made double, but is specially arranged so that of the two concentrically-arranged hollow spindles 9 ^{9a} the outer one—viz., 9^a—which is made shorter than the inner one 9, is made to converge onto or toward the inner one, so that the area of the steam-exit between the two is smallest at, or practically at, the end of the outer spindle, as shown. By this construction the action of the injector 10 is greatly improved and the jet of mixed water and steam leaving the injector is able to be forced against a higher pressure than heretofore. The outer spindle 9^a may be screwed or fitted onto the inner spindle 9 at 15 9^b, the latter being provided with a collar 9^c, against which the end of the outer spindle makes a steam-tight joint. On the other side of this collar the inner spindle is prolonged, as shown at 9^d, and screwed so as to fasten 20 into the steam-passage 12^b, extending through the cap 12. The inner spindle 9 is formed with perforations 9^e, so that steam supplied to it can pass partly to the outer spindle 9^a and two concentric jets of live steam be 25 thereby produced. A double spindle constructed as described can be advantageously used in ordinary injectors.

Fig. 5 shows a further modified construction of the injector suitable for use when it 30 is desired at times to work the injector by live steam admitted through the exhaust-steam nozzle 1 instead of with exhaust-steam, as, for example, when the engine from which the exhaust-steam is obtained is standing. 35 In this case the cap or cover 12 on the end of the injector-casing 3 is in the form of a valve adapted to control the supply of live steam to the exhaust-steam chamber 10 of the injector where it expands, the ordinary wing- 40 valve 14 being preferably left partly open for the purpose, and acts in the same way as the exhaust-steam supplied to the said chamber in the ordinary way. The valve-body 14 carries a hollow live-steam spindle, which may be 45 single, as shown at 9 in full lines, or double, as shown at 9 9^a in full and dotted lines, which extends centrally through the exhaust-steam nozzle 1, and to which live steam is supplied at high pressure from the chamber 50 15 at the supply side of the main valve 16 through a passage 17, controlled by a supplementary valve 18, the spindle 19 of which may extend outward in a direction at right angles to that of the main valve, as shown, 55 or in any other suitable direction.

What I claim is—

1. In an injector, a rotary exhaust-steam nozzle screwed into the injector, gearing located within said casing and adapted to rotate said nozzle, and a regulating-spindle extending to the exterior of said casing and adapted to operate said gearing, substantially as described for the purpose specified.

2. An injector having an exhaust-steam supply chamber with lateral inlet-passage, an endwise-movable exhaust-steam nozzle having an unobstructed inlet end in free commu-

nication with said steam-supply chamber, and a spindle carried by the end of the injector-casing and extending through said chamber 70 and nozzle and out of contact with the latter so as to form therewith an unobstructed annular inlet-opening for exhaust-steam, substantially as described.

3. An injector having an exhaust-steam-supply chamber with lateral inlet-passage, an endwise-movable exhaust-steam nozzle having an unobstructed inlet end in free communication with said steam-supply chamber, and a hollow live-steam spindle carried by the end 80 of the injector-casing and extending centrally through said steam-supply chamber and nozzle, substantially as described.

4. In an injector, a compound live-steam spindle composed of two concentric hollow 85 spindles the outer of which is made shorter than and so as to converge toward the inner one, the area of the steam-exit from the outer spindle being smallest at the free end of said outer spindle, substantially as described. 90

5. In an injector, an endwise-adjustable exhaust-steam nozzle, a compound live-steam spindle carried independently of said nozzle and composed of two hollow spindles that are in communication with each other and the 95 outer of which is made shorter than and to converge toward the inner one the area of the steam-exit from said outer spindle being smallest at the free end of said spindle, substantially as described. 100

6. In an injector, an exhaust-steam-supply chamber with lateral inlet-passage, an end- 105 wise-adjustable exhaust-steam nozzle in free communication with said steam-supply chamber, a cap or cover closing a hole in the end of the injector-casing through which said nozzle can be inserted, and a fixed spindle carried by said cap or cover and extending through but independent of said nozzle, substantially as described. 110

7. In an injector, an exhaust-steam-supply chamber with lateral inlet-passage, an end- 115 wise-movable exhaust-steam nozzle 1 in communication with said steam-supply chamber, a cap or cover closing a hole in the end of the injector-casing through which said nozzle can be inserted, and a hollow live-steam spindle carried by said cap or cover, having its interior in communication with a live-steam passage through said cap or cover, and extending into but independent of said nozzle, substantially as described.

8. In an exhaust-steam injector, an exhaust-steam-supply chamber with lateral inlet-passage, an exhaust-steam nozzle in free 125 communication with said chamber, a live-steam valve carried by the end of the injector-casing and having its main exit in communication with said exhaust-steam-supply chamber, a hollow live-steam spindle carried 130 by said valve and extending into said steam-nozzle, and a supplementary valve for controlling the supply of live steam to said spindle, substantially as described.

9. In an injector, an exhaust-steam-supply chamber with lateral inlet-passage, an end-wise-movable exhaust-steam nozzle 1 in communication with said steam-supply chamber, 5 a worm-wheel fast on the exterior of said nozzle, a worm gearing with said worm-wheel and fixed on a spindle extending to the exterior of the injector-casing, and a fixed spindle extending inward from the end of the injector-casing and passing centrally through

said nozzle, substantially as herein described for the purpose specified.

In testimony whereof I have signed my name to this specification in the presence of two subscribing witnesses.

ROBERT GRUNDY BROOKE.
